UNITED STATES PATENT OFFICE

2,418,580

METHOD OF CONSTRUCTING TILE LINED TANKS

John M. Crom, Washington, D.C.

Application October 20, 1942, Serial No. 462,697

2 Claims. (Cl. 25—154)

1

This invention relates more particularly to tanks adapted to hold acids and like liquids of a corroding character and the invention especially concerns a novel and superior tile lined tank of this nature and for this purpose and the method of constructing the tank.

Whereas lined tanks have heretofore been constructed by first building the tank and thereafter lining it, I propose first to form a horizontal cementitious base for the tank and then to set up adjacent to its marginal edge an annular side wall lining of tiles in edge to edge relation and somewhat spaced with their combined inner faces forming the inner face of the proposed tank wall, and then to project cementitious composition over and onto the combined outer faces of the tiles to a depth providing a unitary wall extending about and in bonding engagement with the tiles. The unitary wall provides the body portion of the tank wall and holds the tiles rigidly therewith as the tank lining. The inner faces of the tiles are acid-resistant and the entire lining is thereafter rendered acid-proof and leakproof by packing the spaces between the tiles with acid-resistant cement and compressing the tank to maintain the tile joints tight.

In constructing the tank I preferably first form the horizontal bottom or base of cement and lay a liner of acid-resisting tiles thereonto. A skeleton form is thereafter constructed around the base and the side wall tiles are supported thereon and held in place preferably by a novel flexible band arrangement hereinafter described. The tank is completed by placing the side wall in compression, preferably both vertically and horizontally, by reinforcement placed around and vertically of the unitary wall and covered with a cementitious layer all as hereinafter specifically described, the compression serving to maintain the side wall tiles tight and leakproof at their joints.

The tank thus constructed is lined with tiles which are substantially an integral part of the tank and maintained tight and leakproof at their joints and the inside surface is sealed against the escape or action of the acid or other liquid to be contained. The novel method of constructing the tank is not only most economical but furthermore produces a tank for the purpose described which is substantially superior to like tanks heretofore known. The primary object of the invention resides in this novel method and construction.

These and other features of the invention will be best understood and appreciated from the following description of a preferred embodiment thereof selected for purposes of illustration and shown in the accompanying drawings in which,

Fig. 1 is a fragmentary plan section through a tank being constructed in accordance with my invention,

2

Fig. 2 is a fragmentary inside elevation thereof, Fig. 3 is a sectional view taken on the line 3—3 of Fig. 2,

Fig. 4 is a fragmentary horizontal section through the tank side wall, and

Fig. 5 is a perspective view of one of the tiles used for the side wall lining.

In constructing the tank I preferably first provide a concrete base 10 for the tank and line the top face thereof with tiles 12 of a character adapted to resist the liquid to be contained in the tank. A tile supporting form preferably of a skeleton-like nature is then erected around the base. The form illustrated comprises uprights 14 mounted in spaced relation around the base and having tile supporting strips 15 in spaced relation vertically thereon. The form is supported from the inside by timbers 16 secured to and connecting the uprights 14. The side wall tiles 17 are of oblong shape and the spacing of the strips is such as to receive and support these tiles on the outer faces of the strips.

The tiles 17 are stacked in edge to edge relation against the outer faces of the strips 15, the longer axes of the tiles extending vertically and each tile preferably being supported against three strips. The form is also so spaced from the edge of the base tiling 12 that only a narrow space is left at the base between the tiles 12 and the inner faces of the tiles 17.

The tiles 17 are slightly spaced apart at their edges and one convenient method of supporting them in place individually on the form embodies the use of flexible bands extending around the outer face of the two edges of each tile and secured at their ends to the form. Two such bands 18 are illustrated as engaging each tile adjacent to its top and bottom ends and attached to the form as by nails 20. Preferably these bands are of rubber or other elastic material for a reason hereinafter described. The form is so constructed that when the tiles 17 are in place thereon their inner faces form the inner face of the proposed tank.

When all the tiles 17 have been placed on the form as illustrated in Fig. 2, I project cementitious composition onto the outer faces thereof, preferably by means of a compressed air gun which is adapted to shoot semi-plastic concrete onto the form in well-known manner, some of the concrete extending into the spaces between the tiles, as shown in Fig. 4. The composition is placed to a depth providing a unitary wall 22 extending about and in bonding engagement with the tiles, the tiles being preferably grooved and undercut as at 24 to provide a positive bond between the tiles and the wall. The wall is thereafter placed in compression preferably both vertically and radially by vertical and circumferential rod reinforcement 26 and 28. This rein-

forcement can be placed either before or after the forming of the wall, as disclosed in my Patent No. 2,315,894, dated April 6, 1943, and when the wall is set the reinforcement is tightened by turnbuckles to place it under tension and the wall under compression. This compression brings and holds the tiles 17 tight and leakproof at and along their cooperative edges. The outer face of the tank is then completed by projecting a layer 30 of cementitious composition over the outer face of the wall, this layer bonding to and completely covering the wall and rods and bonding all the units into a unitary structure.

The inside of the tank is finished as follows after removing the forms 14-16. The bands 18 are severed at the inside faces of the tiles and when the bands are of elastic material the severed ends snap back into spaces between the tiles. The inside face is then finished by packing these spaces with acid-resisting cement 32. Preferably I groove the edges of the tiles as at 34 to provide undercut shoulders for receiving and supporting the cement 32. The cement at 22 seals the outer portions of the spaces and the cement 32 is packed tightly thereinto and flush with the inner faces of the tiles. The spaces between the base tiles 12 and between such tiles and the tiles 17 are likewise packed with the acid-resisting cement at 36.

It should be particularly noted that the tiles 17 are arranged with vertical gaps therebetween and are also preferably spaced apart at their horizontal edges. The function of the gaps is two-fold. They freely permit the necessary shrinkage of the concrete outer wall 22 upon setting of the wall and they provide packing space for receiving the liquid resisting cement 32. Without such open gaps or spacing the layer of tiles would form a rigid barrier against which the shell 22 could not shrink and with the result that the shell would crack and therefore be useless for the purpose required. The tank wall is preferably allowed to set long enough to attain most of its shrinkage before the joints are packed with the cement 32 and this cement is allowed to harden before the tank wall is placed under compression, it being understood that such concrete as projects into the joints from the shell 22 shrinks along with the shell and does not impede the said shrinkage of the shell. The wall is thereafter placed under compression, preferably both vertically and horizontally by reinforcement 26 and 28. This compression brings and holds the tiles in tight contact with the cement 32 at the joints, thus providing and maintaining a leakproof lining throughout the interior wall of the tank, which lining is supported by the unbroken shell 22 bonded and shrunk thereonto. It will be apparent that the shell is relatively thin, as compared to a poured concrete wall, and is quite compressible by the reinforcement to the degree necessary to secure the tight joints.

The primary purpose of the invention is to provide a tile lined tank adapted to hold acids and like liquids of a corroding character and it will be apparent that the lining must be and remain absolutely leakproof if it is to perform this function since any leakage through the lining would permit the acid in the tank to attack and destroy the concrete shell. The primary danger to such action is at the joints and the step of packing the joints with acid resisting cement together with the subsequent placing of the tank

in compression to hold the tiles tight and leakproof at their joints is particularly adapted to preclude such leakage. It will be apparent that slight shrinkage may take place in the joint packing and the subsequent placing of the tank in compression is essential to close up all such shrinkage and bring the tiles into tight contact with and firmly support the packing at the joints.

The completed tank embodies a solid concrete base together with the side walls of preloaded cementitious construction, all tile lined and held under compression and packed to provide an inner face sealed continuously thereover against the action of acids or other liquids to be contained. Furthermore, the tile side wall lining is substantially an integral part of the side wall construction 22-30. The tank is therefore of substantial and superior construction and provides every element necessary to perform the required functions, and the novel method of producing the tank renders its production most economical.

Having thus described my invention what I claim as new and desire to secure by Letters Patent of the United States is:

1. A method of constructing a liquid-resisting tile lined tank, which consists in erecting a tank-like form having outwardly facing tile-receiving and supporting surfaces, mounting an annular layer of liquid-resisting tiles thereon in edge to edge relation wherein their combined inner faces provide the inner face of the tank wall, the tiles of said layer being spaced apart to provide a gap between horizontally adjacent tiles, projecting a layer of cementitious composition over and onto the combined outer faces of the tiles to a depth sealing the outer portions of the spaces between the tiles and providing a unitary wall extending about and in bonding engagement with the tiles, the gaps between the spaced tiles permitting free shrinkage of the wall, removing the form, packing the gaps between the tiles at and outwardly of their inner faces with liquid-resisting cement, and placing and holding the tiles tight and leakproof along the joints at said gaps by placing the tank under compression by the application of steel reinforcement circumferentially and under tension about the outer face of said wall.

2. The method defined in claim 1 in which the tiles are spaced apart at their vertical and horizontal edges, and in which the tank is placed in compression horizontally and vertically by the application of steel reinforcement under tension and extending circumferentially about and vertically of the tank wall, said compression placing and holding the tiles tight and leakproof along their edge joints.
